[57] CLAIM

The ornamental design for a swivel bracket for a camera, as shown and described.

DESCRIPTION

FIG. 1 is a perspective view from the front, top and left side of a swivel bracket for a camera showing my new design; FIG. 2 is a front elevational view thereof (the rear side being a mirror image thereof);

FIG. 3 is a left side elevational view thereof (the right side being a mirror image thereof);

FIG. 4 is a top plane view thereof;

FIG. 5 is a front elevational view thereof, the mount portion shown in an alternate position; and,

FIG. 6 is a front elevational view of a second embodiment of a swivel bracket for a camera.

The broken lines shown in FIGS. 5 and 6 are for illustrative purposes only and form no part of the claimed design.
